DISPENSING DEVICE WITH SAFETY LOCK

Filed Nov. 22, 1928

UNITED STATES PATENT OFFICE

JAMES B. CRAVEY AND PAUL R. PIERSON, OF MONTGOMERY, ALABAMA

DISPENSING DEVICE WITH SAFETY LOCK

Application filed November 28, 1928. Serial No. 321,123.

This invention relates to dispensing devices such as are used for the handling of gasoline, lubricating oils and other petroleum products or in fact any liquids which are usually dispensed by measuring pumps or pumps connected to elevated measuring tanks. More particularly the invention relates to a theft preventing device for such dispensing devices.

The principle objects of the present invention are to provide an ordinary gasoline or oil pump such as is used in dispensing gasoline at the supply stations common on roads and streets, with means whereby unauthorized operation of the pump will not furnish the gasoline or oil to the person endeavoring to steal the same.

A second important object of the invention is to provide an improved arrangement of dispensing pump wherein the suction pipe of the pump may, if desired, be opened to the air so that operation of the pump while the suction pipe is thus open will not result in the pumping of the liquid. This is necessary because it is quite common for thieves to break the locks off the handles of the pumps when the stations are closed for the night and pump the gasoline from the underground tank to the loss of the owner of the station.

A third object of the invention is to provide a device of this character in which the control of the air admission will be so disposed as to be invisible and inaccessible to the unlawful operator.

A fourth object of the invention is to provide a novel device of this character wherein the suction to the pump may be vented from the interior of an adjacent building, say the office of the station, or home of the owner.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and in the drawing, the figure is a vertical elevation partly in section, showing a pumping device connected to an underground storage tank with a venting control remotely situated, as in a building. The control here shown is a by-pass pipe connected to the intake pipe of the pump.

In the embodiment disclosed in the drawing, it will be seen that there is shown a dispensing device of ordinary construction indicated in general at 10 and having within the lower part of its casing a pump 11 provided with the usual operating means and with the usual operating controls. This pump is provided with the usual suction pipe 14 leading from an underground storage tank T and delivery pipe 26.

In the device shown in the drawing there is provided just below the pump 11 a T fitting 16 from which extends a branch pipe 23 which leads off from the suction pipe 14 to a suitable point in the interior of a building or office and within such building or office is provided with an ordinary valve 24 so that the branch 23 may be opened to the atmosphere or closed as desired.

When the operator wishes to shut down the pump for any length of time, as during his absence or at night, he simply opens the valve 24. Under these circumstances operation of the pump will not pump gasoline.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

It may particularly be pointed out that the

invention is in no sense limited to the particular form of pump shown. The pump may be any kind of suction pump, rotary or reciprocating, provided with an elevated storage tank or not, provided with a housing or casting or not.

The present case is in part a continuation of our copending application, Ser. No. 184,389 filed April 26, 1927.

10 The pump, if of the type shown in the drawing by way of illustration, may be operated by a handle or crank 25, and may deliver the gasoline, etc., through pipe 26 connected to a flexible hose 27. A check valve 28 and a hand valve 29 may be provided on the outlet line. A fill line is shown at the right for filling the tank T.

Having thus described the invention, what is claimed as new, is:

20 1. In a device for dispensing liquids, the combination of an underground storage tank, a pump having a delivery pipe and having a suction pipe leading from said tank, a branch pipe concealed from view and connected to 25 said suction pipe at a point concealed from view, said branch pipe being large enough to admit sufficient air to the suction pipe to destroy the suction therein, said branch pipe having an air inlet valve at a point within 30 an inclosure remote from said pump, such branch pipe being wholly independent of the delivery pipe and being in addition to all pipes through which liquid flows during the entire operation of the device, and the said 35 air inlet valve being operable wholly independently of all other parts of said dispensing device.

2. A device as covered in claim 1, in which the air inlet valve is located within a 40 building, and said pump is located outside of said building.

3. In a liquid dispensing device including an underground liquid storage tank, a pump provided with a suction pipe and a delivery 45 pipe and with controls, a branch pipe entering said suction pipe at a concealed point between said pump and said liquid storage tank, said branch pipe being large enough to admit sufficient air to said suction pipe to destroy 50 the suction therein, said branch pipe being concealed from view and leading to a point remote from said pump, and a valve opening and closing the end of said branch pipe remote from said pump, said valve being operable entirely independently of the controls 55 of said pump.

4. In a liquid dispensing device including a liquid storage tank disposed underground, a pump including controls, a suction pipe and 60 a delivery pipe for said pump, a theft preventing device including a branch pipe entering said suction pipe at a point below the surface of the ground, said branch pipe being sufficiently large to admit sufficient air to destroy 65 the suction in said suction pipe, said

branch pipe leading below the surface of the ground to an inclosed space at a point remote from said pump, a locally operable valve opening and closing the end of said branch pipe at said remote point and within said inclosed space. 70

In testimony whereof we affix our signatures.

JAMES B. CRAVEY.
PAUL R. PIERSON.
